UNITED STATES PATENT OFFICE.

CHARLES J. BAILEY, OF BOSTON, MASSACHUSETTS.

DESIGN FOR A BATH-BRUSH.

SPECIFICATION forming part of Design No. 18,222, dated April 3, 1888.

Application filed March 3, 1888. Serial No. 264,771. Term of patent 14 years.

To all whom it may concern:

Be it known that I, CHARLES J. BAILEY, a citizen of the United States, residing at Boston, county of Suffolk, State of Massachusetts, have invented and produced a new and original Design for a Toilet or Bath Brush, of which the following is a specification, reference being had to the accompanying drawing, forming part thereof.

10 The drawing shows in perspective my newly-designed toilet or bath brush.

The leading feature of my design consists in a bath-brush having thereon in profile the female figure a, with uplifted arms c, standing 15 upon a pedestal, b, and bending slightly forward in position to plunge or dive into the water, d.

I claim—

The design for a toilet or bath brush herein shown and described, the same consisting of 20 the female figure a, in profile, standing on the pedestal b, and having uplifted arms c, bending slightly forward in position to plunge or dive into the water.

In testimony whereof I have signed my name 25 to this specification in the presence of two subscribing witnesses.

CHARLES J. BAILEY.
